UNITED STATES PATENT OFFICE.

ROBERT CORNELY, OF PARIS, FRANCE.

EMBROIDERING-MACHINE.

1,143,945.

Specification of Letters Patent. Patented June 22, 1915.

Application filed January 24, 1913. Serial No. 744,007.

To all whom it may concern:

Be it known that I, ROBERT CORNELY, a citizen of the United States, resident of Paris, France, have invented a new and useful Improvement in Embroidering-Machines, which is fully set forth in the following specification.

Sewing, embroidering, festooning or like fancy stitch machines which produce embroidery, scallops, festoons, button-holes, etc., of predetermined designs or shapes which are automatically repeated continuously, are well known as fitted with rotating disks, drums or cylinders provided with a pattern-cam which controls the shape or design of the embroidery or scallops to be produced. This pattern-cam was arranged to control by means of a roller or the like engaging in said cam and by means of suitable transmissions, according to the style of the machine, either the longitudinal displacement of the rotating feed roller, or the lateral oscillations of the needle or needles across the direction of the feed. In order to prevent the wear of the pattern-cam from spoiling the beauty and regularity of the work, it was necessary to make said pattern-cams as large as possible, viz. to give a diameter as large as possible to the disks, drums or cylinders of the pattern-cam, which thus became very heavy. But as these disks or cylinders of the pattern-cam do not perform a continuously rotating motion, but only turn stitch for stitch of the machine, usually by means of a pawl and ratchet wheel or a similar arrangement, so that they have to be started and stopped at every single stitch of the machine; the consequence was that they were heavy to start and heavy to stop, which at high speed occasioned constant shocks and a rapid wear of the machine.

The object of the present invention is to obviate these inconveniences and this result is obtained by the provision of a non-turning viz. a fixed pattern-cam, while on the other hand, the roller or the like which transmits the automatic motion, follows the sinuosities of said pattern-cam.

In the example represented in the drawings, the pattern-cam is formed interiorly of a hollow cylinder, which arrangement has the advantage of protecting the pattern-cam and all organs working within said cylinder against dust and exterior shocks.

Figure 1 is a front elevational view and Fig. 2 is a vertical central sectional view on the line A—B of Fig. 1, showing an embodiment of my invention. Fig. 3 is a plan view of Fig. 1. Fig. 4 is a longitudinal sectional view showing another embodiment of my improvement. Fig. 5 is a vertical sectional view taken on the line C—D of Fig. 4. Fig. 6 is a view in vertical section showing another embodiment of the invention 65 and Fig. 7 is an elevational detail. Fig. 8 is a detail view illustrating a modification.

Referring to Figs. 1, 2 and 3 the bar 1 of the presser foot of the machine is provided with a bracket 2 which ascends and descends together with said bar 1. Bracket 2 is provided with a socket 3 to which the cylinder 4 of the pattern-cam 16 is secured in any suitable way.

The under shaft 5 of the machine is provided with a cam 6 which by means of lever 7 and pitman 8 transmits an oscillating motion to lever 10 which is provided with a pawl 9 which controls ratchet wheel 11. This ratchet wheel 11 is provided with a key 14 which engages in a groove 13 of shaft 12, which thus receives a turning motion while at the same time said shaft 12 can be displaced longitudinally.

Shaft 12 is provided with a roller 15 which engages in the pattern-cam groove 16 thus transmitting to shaft 12 a longitudinal shifting movement according to the shape of the pattern-cam 16 while it rotates, which combined motion is transmitted to the feed roller 17 secured at the other end of shaft 12, and this roller thus feeds the material in the well known manner according to the shape and design of the pattern-cam 16.

Figs. 4 and 5 show an example of an arrangement of a fixed pattern-cam for controlling the lateral displacements of the needle-bar or bars. Main shaft 19 of the machine is provided with an eccentric 20 which by means of pitman 21 moves lever 10, pawl 9 and ratchet wheel 11. The shaft 12 is provided with a groove B' which permits its longitudinal movement while it rotates as described with regard to Figs. 1, 2 and 3 and said shaft 12 is provided with a collar thrust bearing 22 with which engages the suitably arranged end of rod 23, which rod 23 thus moves only longitudinally and does not revolve together with the shaft 12, since the other end of rod 23 is secured to the 110

movable bracket 24—25 of the needle-bar 26 which thus receive a to and fro motion according to the shape of the pattern-cam.

It is clear that the pattern-cam which has been shown as example only, provided interiorly of a fixed cylinder 4, might just as well be provided on the exterior of said cylinder, as illustrated in Fig. 8.

Figs. 6 and 7 show that the pattern-cam 10 may just as well be provided on a non-revolving disk 29 with which engages a roller 28 secured on a lever 27 jointed to the shaft which is rotated and eventually shifted in the same manner as above described.

15 It will be readily understood that by the use of this non-revolvable pattern-cam which forms the object of the present invention, the following results are obtained: (1) Since the cylinder or disk of the pattern-cam does not revolve, the weight of said cylinder or disk is not a drawback and therefore, my invention allows the use of larger pattern-cams which are submitted to less wear and produce a better and more 25 regular work. (2) The cylinder or disk of the pattern-cam remaining motionless, the constant shocks resulting from the intermittently revolving pattern-cams used heretofore are obviated, which allows the 30 machine to be driven at higher speed and with less wear.

I am aware of prior patents in which cams or other means are employed to control and vary the length of zig-zag or laterally-formed stitches which extend laterally from or across a straight line of forward 35 advance of the work. But such lateral variation in the length of stitches and the resulting design of seam thereby formed does 40 not constitute a variation or change in the direction of the seam within the meaning of that language as employed in some of the claims herein.

Claims:

45 1. In a sewing machine adapted to produce seams of predetermined and automatically repeated design, mechanism for relatively shifting the needle and work laterally to change the direction of the seam 50 in conformity with the desired pattern as the work advances through the machine and the formation of the seam progresses, said mechanism comprising a fixed pattern cam, adapted to determine and vary the direction 55 of the seam, a movable member adapted to engage and be guided in its movement by said pattern cam and to relatively shift the needle and work laterally under control of said pattern cam to vary the direction of 60 the seam, and driving connections for actuating said movable member.

2. In a sewing machine adapted to produce seams of predetermined and automatically repeated design, mechanism for 65 relatively shifting the needle and work

laterally to change the direction of the seam in conformity with the desired pattern as the work advances through the machine and the formation of the seam progresses, said mechanism comprising a fixed pattern cam 70 adapted to determine and vary the direction of the seam, a rotary member adapted to engage and follow said pattern cam in its rotation and to relatively shift the needle and work laterally under control of said 75 pattern cam to vary the direction of the seam, and driving connections for rotating said member.

3. In a sewing machine adapted to produce seams of predetermined and automatically repeated design, mechanism for 80 relatively shifting the needle and work laterally in conformity with the desired pattern as the work advances through the machine and the formation of the seam 85 progresses, said mechanism comprising a fixed annular pattern cam surface, a rotary member adapted to engage and follow said pattern cam in its rotation and to relatively shift the needle and work laterally under 90 control of said pattern cam, and driving connections for rotating said member.

4. In a sewing machine adapted to produce seams of predetermined and automatically repeated design, mechanism for 95 relatively shifting the needle and work laterally in conformity with the desired pattern as the work advances and the formation of the seam progresses, said mechanism comprising a fixed annular pattern 100 cam surface, a rotary and longitudinally movable shaft having its axis approximately coincident with that of the annular pattern cam surface and also having a part adapted to progressively contact said pattern-cam during rotation of the shaft to longitudinally move the shaft under control of said pattern-cam, means associated with said shaft to relatively shift the needle and work laterally in accordance with the longitudinal movement of the shaft, and driving connections for rotating said shaft.

5. In a sewing machine adapted to produce seams of predetermined and automatically repeated design, mechanism for 110 relatively shifting the needle and work laterally in conformity with the desired pattern as the work advances and the formation of the seam progresses, said mechanism comprising a fixed part having a cylindrical interior surface formed with a cam-groove therein constituting a pattern for the desired design, a rotary and longitudinally movable shaft having its axis approximately coincident with that of said 115 cylindrical surface and also having a part extending into engagement with said cam-groove, driving connections for rotating said shaft and thereby imparting longitudinal movement to the shaft under 120 control.

trol of the cam-groove, and means associated with said shaft to relatively shift the needle and work laterally in accordance with the longitudinal movement of the shaft.

5 6. In a sewing machine for producing seams of predetermined design to be automatically repeated, a rotary feed member adapted to be displaced transversely of the direction of the feed of the work, a sta-

tionary pattern cam, and a revoluble shaft 10 adapted to be reciprocated by said cam and having connection with said feed-member to displace the same as described.
